US0D1028970S

(12) **United States Design Patent** (10) **Patent No.:** **US D1,028,970 S**
(45) **Date of Patent:** **** May 28, 2024**

(54) **DATA PROCESSING DEVICE**

(71) Applicant: **Siemens Aktiengesellschaft**, Munich (DE)

(72) Inventors: **Jan Andersson**, Erlangen (DE); **Nina Wendt**, Bayern (DE)

(73) Assignee: **SIEMENS AKTIENGESELLSCHAFT**, Munich (DE)

(**) Term: **15 Years**

(21) Appl. No.: **29/756,272**

(22) Filed: **Oct. 27, 2020**

(30) **Foreign Application Priority Data**

Apr. 30, 2020 (EM) 007847959

(51) **LOC (14) Cl.** **14-02**

(52) **U.S. Cl.**

USPC **D14/314**; D14/371

(58) **Field of Classification Search**

USPC D14/126, 305, 307, 314, 335–336, 340, D14/371–372, 374–379, 381–382, 448; D13/162; D24/186; D21/324, 329, 332

CPC G06F 1/16; G06F 1/1601; G06F 21/84

(57) **CLAIM**

The ornamental design for a data processing device, as shown and described.

DESCRIPTION

FIG. 1 is a front elevational view of a data processing device showing our new design;

FIG. 2 is a rear elevational view thereof;

FIG. 3 is a top plan view thereof;

FIG. 4 is a bottom plan view thereof;

FIG. 5 is a right-side elevational view thereof;

FIG. 6 is a left-side elevational view thereof; and,

FIG. 7 is a front, top and right-side perspective view thereof. The broken lines shown in the drawings are for the purpose of illustrating portions of the article and form no part of the claimed design.
